DUAL-HOPPER APPARATUS FOR FILLING CONTAINERS

Peter S. Magna, Pittsburg, and William E. McCormick, Concord, Calif., assignors to United States Steel Corporation, a corporation of New Jersey

Application May 1, 1957, Serial No. 656,460

4 Claims. (Cl. 141—263)

The present invention relates generally to apparatus for packaging articles in containers and more particularly to an improved container-filling guide especially suitable for use in packaging nails and similar articles.

In high-speed automatic carton packaging of nails it is necessary to utilize a guide or funnel inserted in the top of the carton to properly control the flow of nails being dumped into the carton during the filling stage so that high speed operations can be maintained.

In one type of modern nail packaging apparatus a turntable supports a plurality of carton-loading units adjacent its periphery. Each of these units includes a base adapted to support a nail carton, a funnel or guide supported on the base for movement into and out of the open top of the carton, and a hopper having a retractable spout for dumping nails into the funnel or guide. An example of this type of equipment is described and claimed in Warner application Serial No. 601,140, filed July 31, 1956. In the operation of this type of nail packaging equipment empty cartons are loaded onto each base at one station adjacent the turntable and the funnel or guide is lowered into the carton. The turntable is revolved to advance each unit to a loading station where a predetermined quantity of nails are dumped into the hopper of the unit. Then as the turntable revolves the carton is vibrated as the nails are dumped into the carton from the hopper through the funnel. When the loaded carton reaches the first station again, the funnel or guide is lifted out of the carton and the carton is pushed off onto a conveyor for delivery to another location for sealing and tying in order to achieve optimum efficiency and a power lifter is provided adjacent the carton placement station of the apparatus for lowering and raising the funnel or guide assembly. The funnel or guide is lifted to a minimum height above the base as a filled carton is pushed therefrom and an empty one put in its place so that as little time as possible will be required for this operation. As a result the bottom of the funnel or guide just clears the top of the carton when the funnel or guide is in lifted position.

A serious disadvantage inherent in the type of equipment just described is caused by the tendency of the nails to frequently pile up in the funnel or guide above the top of the carton. When this happens the mound of nails piled up above the top of the carton are scraped off of the carton and spill onto the turntable when the loaded carton is pushed out from under the funnel or guide.

It is accordingly, an object of the invention to eliminate the disadvantage just described by providing a two stage container-filler guide apparatus including two nested hoppers adapted to be inserted in the open top of a container for guiding articles thereto and to be removed from the filled container in a manner whereby the lowermost hopper is not removed from the filled container until the uppermost hopper has been lifted a predetermined distance.

It is another object of the invention to provide a two stage container-filler guide apparatus as set forth above in which a fin-insert is removably disposed in the uppermost hopper for spreading and promoting the alignment of articles being dumped into the container through the hoppers.

2

These and other objects will become more apparent after referring to the following specification and attached drawings, in which:

Figure 1 is a plan view of a rotary nail packaging machine having the apparatus of the invention incorporated therein;

Figure 2 is a side elevational view of the apparatus of the invention in raised position;

Figure 3 is a view similar to Figure 2 showing the apparatus of the invention in lowered position;

Figure 4 is a plan view of the secondary hopper of the apparatus of the invention;

Figure 5 is a plan view of the primary hopper of the apparatus of the invention;

Figure 6 is a plan view of the fin-insert of the invention;

Figure 7 is a side elevational view partly in section of the fin-insert of Figure 6; and

Figure 8 is a vertical sectional view showing the hoppers and fin-insert of the invention in nested position.

Referring more particularly to the drawings reference numeral 2 designates generally the device of the invention which for purposes of illustration will be described and shown as used in conjunction with a rotary nail packaging machine, indicated generally at 4, of the type disclosed and claimed in the aforementioned Warner application, and a power lifter, designated generally by reference numeral 6, of the type disclosed and claimed in Prenk application Serial No. 580,309, filed April 24, 1956. The power lifter 6 is disposed adjacent to the packaging machine 4 at the carton placement station, as shown in Figure 1. The specific details of the nail packaging machine or of the power lifter are not pertinent to the present invention, and therefore, description of only those elements of the packaging machine and power lifter necessary to a complete understanding of the present invention will be included herein.

The nail packaging machine 4 includes a rotary plate or table 8 which supports a plurality of the two stage container-filler assemblies of the invention spaced about the periphery thereof. All of the container assemblies 2 are identical, each assembly including a base plate 10 adapted to support a carton or container C. A pair of spaced vertical guide rods 12 project upwardly adjacent one edge of the base plate and a sleeve 14 is telescoped on each of the rods 12 for supporting a primary hopper 16. Hopper 16 is attached to the upper ends of the sleeves by means of a bracket 18. A lift plate 20 whereby the sleeves 14 may be raised by the power lifter is connected with and extends between the sleeves at a point intermediate their ends. Lift plate 20 is adapted to be engaged by the retractable lifting bar 22 of the power lifter 6 to raise the lower sleeves 14 on the rods 12 to thereby raise and lower hopper 16 in relation to a carton supported on the base 10. A flange 24 projects laterally from the edge of the hopper 16 opposite to the bracket 18 and supports a depending lift rod 26 the function of which will become apparent hereinafter.

A second hopper 28 is disposed below and is dimensioned to nestingly receive the primary hopper 16. A pair of spaced vertical guide rods 30 project upwardly from the base 10 spaced from and parallel with the pair of guide rods 12. A sleeve 32 is slidably telescoped on each of the rods 30 for supporting secondary hopper 28 for vertical movement. The hopper 28 is connected with the upper ends of the sleeves 32 by means of a bracket 34 which projects from the edge of hopper 28 and extends outwardly and is welded to or otherwise rigidly connected with sleeves 32. A flange 35 is provided between the sleeves 32 and has a center hole 36 for accommodating the lift rod 26 which depends from primary

hopper 16 and passes through the flange 35. The bottom portion of rod 26 is threaded for carrying a stop member in the form of a lock nut 38 having a diameter greater than the diameter of hole 36. The nut 38 is adapted to engage the undersurface of flange 35 to lift secondary hopper 28 as the primary hopper is being lifted after the primary hopper has been raised a predetermined distance clear of secondary hopper 28. The distance hopper 16 is raised before hopper 28 is lifted can be varied by adjustment of nut 38 along the threaded portion of rod 26.

In operation, power lifter 6 is actuated to project lifter bar 22 so that it engages lift plate 20 and lifts it to elevated position to raise hopper 16 away from base 10. As the hopper 16 is raised and before it reaches the end of its path of travel, nut 38 engages the underside of flange 35 and lifts hopper 28 as hopper 16 continues to be raised. An empty carton C is then placed in position under the elevated hoppers 16 and 28 and the power lifter is again actuated to cause lowering of lifter bar 22 and disengagement thereof from lift plate 20 to lower hopper 28 into the open top of carton C and nest hopper 16 within hopper 28. The rotary table 8 is then actuated to advance the carton C with hoppers 16 and 28 therein to the next station of the packaging machine.

After the carton C has been loaded with the desired quantity of nails, it is returned to the carton placement station for removal. When the filled carton reaches the carton placement station power lifter 6 is actuated to raise lifter bar 22 after it has been projected into engagement with the underside of lift plate 20. Raising of lift bar 20 causes the hopper 16 to initially rise clear of hopper 28 causing any nails that may have piled up in hopper 16 to be agitated so that they pass freely through hopper 28 into the carton C. Hopper 28 is provided with a larger opening than hopper 16 to insure the free flow of piled-up nails through hopper 28. After hopper 16 is raised clear of hopper 28 the nut 38 on the bottom of lift rod 26 engages the underside of flange 35 to lift hopper 28 clear of carton C during continued raising of hopper 16. Then, after filled carton C is removed an empty carton is put in its place and the packaging cycle is repeated.

When larger size nails, 16d or larger, are being packaged it has been found advantageous to utilize a fin-insert 40 in the primary hopper 16 to spread and align the nails as they flow into the carton during filling. As shown in Figure 8, the fin-insert 40 may be removably inserted in primary hopper 16. The fin-insert 40 includes a frame 42 which is dimensioned to be nested into and supported by the primary hopper 16. Four fin plates 44 are welded or otherwise rigidly connected at their upper ends to the frame 42 in spaced parallel relation to each other. The plates 44 depend from the frame 42 downwardly into the carton C through hopper 28, as shown in Figure 8, after the hopper 28 is lowered into the top of carton C. When the nails are dumped through the fin-insert they are separated and aligned since the space between adjacent plates 44 is less than the length of the nails being packaged. The spacing between plates 44 depends on the size of nails being packaged. Handle 50 may be provided on the inside of frame 42 to facilitate handling of the fin-insert.

Notches 46 and 48 may be provided in the upper edges of the two center plates 44' and 44'', respectively, to improve the separating and aligning effect of the fin-insert. For optimum results we have found it desirable to pitch the notches in one plate opposite to the notches in the other plate, as shown in Figure 7.

While one embodiment of our invention has been shown and described, it will be apparent that other adaptations and modifications may be made without departing from the scope of the following claims.

We claim:

1. A two stage container-filler guide apparatus com- 75

prising a base adapted to support an open top container, a first pair of spaced vertical guide rods projecting upwardly from said base adjacent one side thereof, a sleeve slidably telescoped on each of said rods, a first hopper attached to and supported by said sleeves for vertical movement toward and away from said base, a lift plate extending between and connected with said sleeves at a point intermediate the ends thereof, a second pair of spaced vertical guide rods projecting upwardly from said base spaced from and generally parallel with said first pair, a sleeve slidably telescoped on each of the rods in said second pair, a second hopper adapted to fit into the open top of a container disposed on said base attached to and supported by said last named sleeves for vertical movement toward and away from said base, said second hopper being attached to said last named sleeves by means of a lug projecting laterally from said second hopper, said lug having a center hole therethrough, said first hopper being dimensioned to fit into said second hopper, and lifting means depending from said first hopper adapted to engage said lug to thereby lift said second hopper as said first hopper is being raised after said first hopper has been raised a predetermined distance, said lifting means including a lift rod depending from said first hopper and slidably fitting into the center hole of said lug, and stop means on the lower end of said lift rod adapted to engage the undersurface of said lug.

2. A two stage container-filler guide apparatus as defined by claim 1 characterized by said stop means being adjustable along a portion of the length of said lift rod.

3. A two stage container-filler guide apparatus comprising a base adapted to support an open top container, a first pair of spaced vertical guide rods projecting upwardly from said base adjacent one side thereof, a sleeve slidably telescoped on each of said rods, a first hopper attached to and supported by said sleeves for vertical movement toward and away from said base, a lift plate extending between and connected with said sleeves at a point intermediate the ends thereof, a second pair of spaced vertical guide rods projecting upwardly from said base spaced from and generally parallel with said first pair, a sleeve slidably telescoped on each of the rods in said second pair, a second hopper adapted to fit into the open top of a container disposed on said base attached to and supported by said last named sleeves for vertical movement toward and away from said base, said second hopper being attached to said last named sleeves by means of a lug projecting laterally from said second hopper, said first hopper being dimensioned to fit into said second hopper, lifting means depending from said first hopper adapted to engage said lug to thereby lift said second hopper as said first hopper is being raised after said first hopper has been raised a predetermined distance, a fin-insert removably telescoped in said first hopper, said fin-insert including a plurality of spaced vertical plates attached at their upper ends to a frame, said frame being dimensioned to fit into and be supported by said first hopper, said plates being of such length as to extend substantially to the bottom of said container when said hoppers are in lowered position and said second hopper is disposed in the open top of said container.

4. A two stage container-filler apparatus as defined by claim 3 characterized by at least two adjacent vertical plates of said fin-insert having pitched notches in the top-edges thereof, the notches in one of said adjacent plates being pitched in the direction opposite to the pitch of the notches in the other of said adjacent plates.
